OIL BURNER

William G. Latimer, Detroit, Mich., assignor to
 Kelvinator Corporation, Detroit, Mich., a corporation of Michigan

Application September 2, 1932, Serial No. 631,571

2 Claims. (Cl. 158—42.4)

The present invention relates to heating systems and more particularly to burners using oil for the fuel. This application is a continuation in part of my copending application S. N. 488,521, filed October 13, 1930, now Patent No. 2,011,901.

An object of the invention is to provide a safety valve in the fuel line for preventing the flooding of the burner in the event of abnormal operation. To carry this out I provide a continuous operating motor for supplying air for supporting combustion and utilizing a governor operated by the motor for maintaining the safety valve open only as long as the motor is operating normally and also utilizing a thermostat responsive to the temperature of the burner for maintaining the safety valve open only when the burner is heating above a predetermined minimum temperature.

Other and further objects and advantages will be apparent from the following description, reference being had to the accompanying drawings wherein a preferred embodiment is disclosed.

Figure 1 is a vertical central longitudinal section through the burner;

Figure 2 is a top plan view with parts thereof shown in section;

Figure 3 is a view similar to Figure 1 showing the burner frame in section, the section being taken on line 4—4 of Fig. 2;

Figure 4 is a sectional view taken on line 5—5 of Figure 3;

Figure 5 is a bottom plan view of a portion shown in Figure 3.

Figure 6 is a sectional top plan view of the end 35 of the burner;

Fig. 7 is a fragmentary plan view, showing the governor control mechanism illustrated in Fig. 2 but on a larger scale;

Fig. 8 is a view of the mechanism shown in Fig. 40 7 but showing the arm S² in a different position;

Fig. 9 is a sectional view taken on line 12—12 of Fig. 2;

Fig. 10 is a perspective view of a thermostatic control mechanism;

Fig. 11 is a cross sectional and fragmentary view of the gas burner shown in Fig. 1 but on a larger scale.

A shelf C is provided for supporting the motor H. This shelf is preferably formed integral with 50 a vertically extending plate C' which forms a closure for the fuel door opening of a furnace. Projecting inwardly from this plate or closure and preferably formed integral therewith is a cylindrical casing C² which extends to substantially the central plane of the furnace fire pot

and has mounted at its inner end a rotary burner as hereinafter described.

The burner is of that type in which the fuel is fed outward over a revolving disc and is discharged from the periphery of this disk to produce the flame. However, the construction differs radically from those usually employed, first, in the manner of feeding and distributing the liquid fuel thereon and second, in the means employed for preventing combustion or overheating of the fuel until it is discharged from the periphery of the burner disc, the detailed construction being as follows:

D is a disc preferably formed of sheet metal and integral and coaxial with a cylindrical sleeve portion D'. Between the cylindrical portion D' and the disc is a slightly flaring or conical portion D² which extends outward beyond the plane of the disc and is then return bent at D³ with a substantially cylindrical portion D⁴ extending 15 backward and merging into the disc. The disc D is mounted upon a spider E which also carries a disc E' spaced from the disc D. The spider E is provided at its center with the hub E² detachably secured to a shaft F preferably by a threaded engagement therewith. This shaft is journaled in bearings G which are preferably carried by an inner tubular housing member G' mounted within and secured at C⁴ to the outer cylindrical housing C². The opposite end of the shaft F is connected 20 to the shaft of the motor H preferably through the medium of a universal joint H' permitting of slight inaccuracy in alignment. Thus the shaft will be driven at motor speed and will communicate its movement first to the spider E and then 25 to the disc D and sleeve D'.

The fuel is supplied to the burner through a nozzle I which is arranged to discharge the liquid at the base of the flaring portion D² of the sleeve D'. The sleeve D' extends into a housing G² at 40 the inner end of the housing G' and which forms an air chamber through which air is to be supplied to the burner. The arrangement is such that the sleeve D' is in close proximity to an annular bearing G³ in the housing G² to form practically a sealed joint and beyond this bearing is an annular portion G⁴ which extends in proximity to the disc D. On this annular portion G⁴ is mounted a non-revolute disc J which is spaced from the disc D a sufficient distance to permit the 50 passage outward of the liquid fuel film but close enough to protect the fuel from ignition until it is discharged from the periphery of the disc. Thus in operation the fuel discharged from the nozzle I will first come in contact with the outer 55

surface of the conical portion D² of the sleeve D' and through the combined action of capillarity and centrifugal force will be fed spirally outward on the revolving cone. This continues until the 5 fuel reaches the return bend D³ where its progress is checked by the cylindrical return bent portion D⁴ so that by the time the fuel reaches the disc D it is quite uniformly distributed. From this point 10 centrifugal action causes the film to move radially outward until it is finally discharged from the periphery of the disc D. The operation of the burner will be fully described hereinafter, but the effect of the mechanism thus far described is to produce a uniformly distributed film of 15 liquid fuel upon the peripheral portion of the disc D and without regard to whether the quantity of fuel discharged by the nozzle I is large or small.

To render the fuel ignitable it is necessary that 20 it should be raised in temperature to near the vaporizing point and to support combustion there must be supplied the proper quantity of air preferably also preheated. The heating of the fuel is effected by surrounding the disc D with an annular member J' which as will be hereinafter explained, is maintained at a temperature above the vaporizing point of the fuel. Thus the film of fuel which is discharged from the periphery of the disc will be vaporized when in proximity to 25 the member J' and will be discharged from the outer end of said member as a combustible gas burning in close proximity thereto. A portion of the heat of combustion will be conducted back through the member J' and will thus maintain 30 said member at the desired temperature. It is, however, necessary to first raise the temperature of the member J' by other means and to this end I have provided a preheating gas burner K. This is preferably formed by a disc K' secured 35 to and extending outward from the disc J and fashioned to form an annular channel K² which abuts against a flange C³ at the outer end of the tubular housing C². A gasket K³ seals the joint between the disc K' and flange C³ so as 40 to form a gas tight conduit which communicates at one point with a supply gas conduit K⁴ extending parallel to the casing C² from outside the furnace door. The outer wall of the channel K² is perforated at K⁵ to form gas jets adjacent 45 to the periphery of the member J', and an annular shield K⁶ confines the gas within only a restricted channel between the same and a flange J² upon the member J'. Thus in starting, when 50 gas is supplied through the conduit K⁴ it will burn just outside the restricted passage between the member K⁶ and flange J² and will supply sufficient heat to the member J' for the initial 55 vaporization of the liquid fuel.

The air for supporting combustion is supplied 60 to the flame through the space between the discs D and E'. This space communicates through the interior of the sleeve D' with the chamber within the housing G². Mounted on the housing G² is a damper or air valve L which when open will 65 establish communication between the chamber in the housing G² and the space within the cylindrical housing C². The air is propelled longitudinally through the housing C² by means of a suitable fan O or other air propelling device 70 driven by the motor, and as shown this fan is mounted upon the universal joint H' and is arranged within a housing O' between the motor H and the flange C'. Whenever the damper L is opened a portion of this air will pass into the 75 housing G² and through the space between the

discs D and E' radially outward against the flame. The valve L is preferably thermostatically controlled and to this end is mounted on a rock shaft L' passing horizontally outward through the cylinder C² and having attached at its outer end a spiral thermostat L³ of the bi-metallic type. When the parts are cold the damper or valve L will be substantially closed but after the burner is heated the thermostat L³ by expanding will rock the shaft L' and open the valve. The degree to which it is opened depends upon the temperature of the casing which in turn depends upon the size of the flame that is issuing from the burner. Consequently whenever the flame is increased by a greater supply of liquid fuel the increased heat will affect the further opening of the valve L so as to supply additional air for the flame. A further function that is performed by the passage of air through this course is the cooling of the shaft and inner portions of the 20 disc E' while the absorbed heat will raise the temperature of the air to increase its efficiency in supporting combustion. Further protection against overheating the shaft and connecting parts is through one or more secondary shields 25 M which are arranged outside of the disc E' to the peripheral portion of which they are attached. Thus air pockets are formed between the shields M and the disc E' which lessens the amount of heat that can penetrate to the disc E'. 30

As shown in Figure 1 a semi-cylindrical shield N surrounding a portion of the housing C² forms a channel for the air through which a portion of the air passing inward through the housing C² will be returned outward through the ports N² 35 channel N¹ and ports N³ and will be discharged outside of the furnace. This circulation of air will be constant during the operation of the furnace and will therefore prevent the overheating of the housing C² and the air passing there-through. This in turn will prevent overheating 40 of the bearings G. As a further precaution the inner housing G' is supported within the housing C² by members of restricted cross section such as the screws C⁴ and dowel pin C⁵ so that very little 45 heat can be conducted inward through these members.

The gas conduit passes through the shelf and connects to pipe K⁴ leading to the burner K.

The amount of fuel fed to the burner may be 50 either manually or automatically controlled. Preferably it is automatically controlled through thermostatic means actuated by room temperature and serving to open or close the liquid fuel supply valve. Any suitable construction may be 55 employed for this purpose and as this forms no part of the present invention further description is omitted.

The valve for controlling the admission of fuel may be located at any convenient point external 60 to the furnace but in order to guard against accidental discharge of fuel an automatic control valve is also employed. This valve R is preferably of the diaphragm control type and is located adjacent to the shelf C. As shown, it is beneath 65 the shelf and comprises a ball R' centrally above a flexible diaphragm R² having the stud R³ secured thereto which when moved upward will press the ball to its seat. Beneath the diaphragm R² is a lever R⁴ having one arm engaging 70 the stud R³ and its opposite arm provided with a weight R⁵. The arm of the lever which engages the stud R³ also bears against a vertical rod R⁶ which passes through the shelf C and upward through the casing O' and being provided at its 75

lower end with a laterally extending arm R^7 passing out from said casing and having a handle R^8 in a position for manual operation to lift the rod R^6 . S is a movable stop which in one position 5 is in the path of the rod R^6 so as to prevent the lifting of the rod R^6 . This stop is provided with a slot which receives a stud S^1 which extends downwardly from the free end of a horizontal lever S^2 fulcrumed at S^3 and bifurcated to embrace the shaft F .

Upon the shaft F is a centrifugal governor T having a slidable sleeve T' actuated by a spring T^2 to bear against the lever S^2 in a direction to withdraw the stop S from the path of the rod R^6 . 15 The sleeve is actuated in the opposite direction by links T^3 connecting it to the weighted arms T^4 . Arms T^4 are pivotally carried by a collar T^5 secured to a shaft F , which arms, when thrown out centrifugally, will overcome the tension of spring 20 T^2 . The stop S is also connected to a horizontal rod S^4 which extends inward through the housing C^2 through a bearing S^5 on the housing G^2 . A spring S^6 between this bearing and a collar S^7 on the rod yieldably holds the stop S extended to be 25 in the path of the rod R^6 .

In the event the fuel heating member J' should cool to such low degree that the fuel is not properly vaporized to support proper combustion, as for example, in case the fuel supply is exhausted, 30 means is provided for preventing flow of fuel to the burner after the fuel tank is replenished. A bi-metallic thermostat U , similar to spiral thermostat L^3 , is employed for this purpose. This thermostat when cooling will rock a bell-crank 35 lever U^1 which in turn will move the rod S^4 to the right (as viewed in Fig. 4) causing stop S to move to the right. The bell-crank lever U^1 is loosely mounted on the rod L' and comprises an arm U^2 which lies in the path of spiral thermostat U and 40 is engaged by the end of the thermostat and forced upwardly when the thermostat cools. The bell-crank lever U^1 includes a depending arm U^3 arranged to engage the projection S^8 on the rod S^4 .

The spiral thermostat U being disposed adjacent the heating ring J^1 , it is responsive to the temperature thereof, therefore when the ring cools the thermostat will cool to rock the bell-crank lever U^1 causing the arm U^3 to move the projection S^8 to the right. This movement 45 causes the stop S to release rod R^6 whereby the weight R^5 is effective to close the valve R^1 to shut off the flow of fuel to the burner.

As long as the motor is operating at its proper speed and as long as the ring J^1 is heated above 50 a predetermined minimum temperature, the stop is over the rod R^6 and maintains the safety valve R^1 open. However, on failure of proper motor operation or on decrease of temperature of the ring J^1 , for any reason, below a predetermined 55 minimum, the stop S is moved to render the weight R^5 effective to close the valve R^1 .

If it is desired to immediately run the burner the gas starter may be first lighted before the insertion of the burner and is then run for a sufficient length of time to do the preliminary heating. The thermostat U will then be heated sufficient to release the stop S so that the spring S^6 will be free to move said stop S over the rod R^6 when the said rod is depressed. The motor is 60 then started which communicates rotary motion to the shaft F and disc D after which the liquid fuel valve is opened by depressing rod R^6 by pushing downwardly on handle R^8 which is connected with arm R^7 . This permits the feeding of the fuel 65 through the nozzle I . The thermostat U then 70

being heated, the spring S^6 will move the stop S over rod R^6 after the motor attains its normal operating speed and has retracted sleeve T' . Fuel, as before described, passes first on the inclined or flaring portion D^2 of the sleeve around 75 the return bend D^3 and back on to the face of the disk D . The outer portion of the disc has already been heated so that the film of oil passing radially outward meeting the hot portion of the disc will be vaporized and will issue as a stream of gas from the periphery of the disc. At the same time air which has passed from the fan through the space within the conduit C^2 will 10 reach the partly open valve L and a portion will pass into the housing G^2 and then through the space between the discs D and E , striking against the flame at the periphery of the disc. This will support smokeless combustion but as the air is not commingled with the gas until the air reaches the peripheral outlet for the fuel, the flame will 15 be white. In other words, a flame that is high in radiant heat is produced, this being the most efficient way of heating the furnace. The construction is one which requires very little attention after it is once started, but if for any reason it 20 should be required to clean the burner this may be easily accomplished by swinging the burner out from the furnace chamber and detaching the rotary disc from the end of the shaft.

The annular groove which is formed by the return bent portion D^3 of the disc constitutes in effect a well in which a certain amount of the liquid fuel is temporarily detained. The larger the capacity of this well the longer the fuel will be detained, which modifies both the degree of 25 heat which is imparted to the fuel and the cooling effect on the disc. Due to this fact I am enabled to adapt my burner for either mild or very cold weather by merely exchanging discs. Thus the greatest efficiency is obtained when 30 the burner is operating low, as in the spring and fall of the year, when used with a disc and a comparatively shallow well but in mid-winter greater efficiency is obtained by using a disc having 35 a deeper well. The changing of the discs 40 is so easily effected that this method of operation 45 may be much more satisfactory than retaining the one construction for all seasons of the year.

Where the burner is operating low, it is highly desirable to maintain uninterrupted feeding of 50 the liquid fuel as otherwise there would be danger of the burner going out. It is, however, difficult to maintain a continuous liquid stream where the quantity is small but I have avoided this difficulty by placing the discharge end of the nozzle I in very close proximity to the surface D^2 on which the liquid is discharged. This has the effect of maintaining the continuity of the liquid stream due to capillarity, whereas if the nozzle were spaced further from the revolving surface the liquid might break up into drops. Furthermore, a positive propulsion force for the fuel is exerted as an air seal is formed which 55 prevents back atmospheric pressure against the fuel in the nozzle and therefore a suction effect 60 is produced by the revolving disc. Thus the liquid fuel will be fed successfully however small the quantity.

By my improved arrangement, the fan O not 65 only supplies air for supporting combustion, but also provides for cooling the moving parts of the burner within the furnace. A blast of cool air is continuously forced over the moving parts to 70 thus keep them sufficiently cool even though the air valve L is closed, or substantially closed. 75

Some air at all times, is permitted to flow over the working parts, which air expelled through the ports N^2 channel N^1 and ports N^3 to the exterior of the furnace or through the housing U^4 5 for the bell-crank U^1 and thermostat U , which housing opens into the furnace and air passing through said housing U^4 prevents excessive heating of these operating parts.

While the form of embodiment of the present 10 invention as herein disclosed constitutes a preferred form, it is to be understood that other forms might be adopted, all coming within the scope of the claims which follow.

What I claim as my invention is:

15 1. A fluid fuel burner comprising in combination, a rotating fuel feeding device, a fuel line, a valve in the fuel line, said valve being urged normally to a closed position, means responsive to a predetermined temperature of the oil burner, 20 means responsive to the speed of the rotating device, and a latch cooperating with the tem-

perature responsive means and to the speed responsive means and connections between said latch and said temperature and speed responsive means, whereby said latch is rendered operative to hold said valve open only when the burner 5 temperature and the speed of the rotating device simultaneously exceed predetermined minimum values.

2. A fluid fuel burner comprising in combination, a rotating fuel feeding device, a fuel line, a valve in the fuel line, said valve being urged to a closed position, means responsive to a predetermined speed of the rotating device, means responsive to a predetermined temperature of the oil burner, and a latch cooperating with the speed 10 and temperature responsive means and dependent jointly upon the speed of the rotating device being normal and upon the temperature of the oil burner being normal for holding the valve 15 open. 20

WILLIAM G. LATIMER.
